UNDERREAMER

Myles G. Schutte and Norman L. Schutte,
Houston, Tex.

Application May 25, 1944, Serial No. 537,296

2 Claims. (Cl. 255—76)

1

This invention relates to an underreamer.

An object of the invention is to provide a tool for enlarging the lower ends of holes in the earth for receiving concrete in foundation work.

Another object of the invention is to provide an underreamer which may be lowered in a previously formed hole and which is provided with reaming blades that will be gradually expanded as the tool is rotated and will gradually enlarge, or underream, the bore hole.

It is a further object of the invention to provide an underreamer that will receive and retain the loose earth, delivered thereto by the reaming blades, and which may be withdrawn from the bore with the tool.

With the above and other objects in view the invention has particular relation to certain novel features of construction, operation and arrangement of parts, an example of which is given in this specification and illustrated in the accompanying drawings, wherein—

Figure 1 shows a side view of the tool with the reaming blades collapsed.

Figure 2 shows a vertical sectional view taken on the line 2—2 of Figure 1.

Figure 3 shows a cross sectional view taken on the line 3—3 of Figure 2.

Figure 4 shows an elevational view, partly in section, showing the reamer blades expanded.

Figure 5 shows a top plan view showing the driving shaft in section with the reamer blades expanded, and

Figure 6 shows a bottom end view.

Referring now more particularly to the drawings, wherein like numerals of reference designate the same parts in each of the figures the numerals 1, 1, designate the vertical side plates which are spaced the required distance apart.

Secured to the lower ends of these side plates there is the circular lower end plate 2 which has the elongated inlet openings 3, 3 therethrough with the depending scrapers 4, 4 formed integrally with said plate behind the slots 3 and pitched forwardly so that the loose earth on the bottom of the bore will be forced through the slots 3 as the underreamer is turned.

The plates 1 have the diagonal slots 5, 5 therethrough at substantially right angles to each other as indicated in Figure 4. Around these slots the material of the plates 1 is thickened as shown more clearly in Figure 2 to provide wider bearing surfaces.

Over the upper ends of the plates 1 and spaced therefrom there is a hood 6 in the shape of a hol-

2

low cylinder closed at its upper end by an upper end plate 6' to which said plates are secured.

The upper ends of the plates 1 have the vertical slots 7, 7. Extending through the slots 7 there is the rod 8 which is retained against displacement by means of the cotter keys 9, 9.

The lower ends of the side plates 1 may be welded to the lower end plate 2 and their upper ends may be welded to the top and sides of the hood 6.

Working against the inner sides of the plates 1 are the reamer blades 10, 10.

These blades 10 have transverse circular openings through their upper end forming bearings 15 through which the rod 8 extends and extended through the slots 5 and through circular openings the corresponding blades 10 are the bolts 11 which have enlarged outer end heads and nuts screwed on their inner ends.

20 Rotatably mounted on the bolts 11 are the anti-friction roller sleeves 12 which run in the slots 5 as indicated in Figure 2.

The upper end plate 6' of the hood 6 has a rectangular opening 13 therethrough, forming a bearing through which there is extended a tubular coupling member 14 which is rectangular in horizontal cross section. This coupling fits snugly through the bearing 13 and welded to the top of the hood on opposite sides of the coupling are 25 the transverse bars 15, 15 provided for additional strength.

The lower end of the coupling 14 has a transverse opening forming a bearing through which the rod 8 extends, as shown in Figures 2 and 3 35 and fitted on said rod between the blades 10 and the coupling 14 are the spacers 16, 16 one on each side.

A driving shaft 17 may be inserted into the coupling 14 and secured therein by the cross pin 40 18 and by means of which the underreamer may be turned.

It will be noted that the reaming blades are flared downwardly and have the forwardly curved portions 19, 19 which terminate in cutting edges.

45 The tool may be lowered into the hole to be underreamed and as lowered the cross rod 8 will be at the upper ends of the slots 7 and the bolts 11 will be at the upper ends of the slots 5 and the reaming blades will be retracted. When the 50 underreamer lands on bottom the pilot 20 will penetrate into the earth and hold the tool centered. The tool is now rotated and the weight from above will gradually force the reaming blades outwardly and the lower end of the bore hole will be gradually enlarged, the cuttings be-

ing forced inwardly by the forwardly curved portions 19 onto the bottom end plate 2 and when the underreamer is withdrawn from the bore the cuttings will be withdrawn with it to the ground surface.

The hood 6 will fit rather snugly in the bore thus steadyng the tool in operation. As the tool is lowered the air beneath the hood may readily escape through the openings 21.

The side plates 1, 1 may be reinforced, within the hood 6, by the cross plates 22, 22 which may be welded thereto as shown in Figure 3.

What we claim is:

1. A reamer for enlarging the lower ends of earth bores, comprising spaced side plates having opposed vertical slots adjacent their upper ends and opposed diagonal slots beneath the vertical slots and arranged at substantially right angles to each other, a lower end plate disposed at substantially right angles to the side plates and fixed to the lower ends thereof, a plate fixed to the upper ends of the side plates and disposed at substantially right angles thereto and having a polygonal opening forming a bearing, a polygonal driving member slidably fitted through said bearing, a rod extending transversely through the driving member and whose ends work in the respective vertical slots, reamer blades adjacent the inner sides of the respective side plates and which are flared downwardly and whose forward

margins are formed into forwardly curved cutting edges and whose upper ends are pivoted on said rod, means attached to the reamer blades and working through said diagonal slots whereby the lower ends of the blades are caused to move outwardly upon downward movement of the blades, relative to the side plates, and are caused to move inwardly upon upward movement of the blades, relative to the side plates.

2. A reamer comprising an earth retainer composed of two spaced vertical side plates having vertical slots adjacent their upper ends and having diagonal slots beneath the vertical slots and a lower end plate secured to the lower ends of the side plates, an upper end plate secured to the upper ends of the side plates and having a polygonal opening therethrough, a rod extending through the upper end slots of the side plates, a driving member slidably fitted through the opening in the upper end plates, said rod extending through said driving member whereby the tool may be rotated, reaming blades whose upper ends are pivotally connected to the rod, means connected to said blades and working through said diagonal slots whereby the lower ends of the blades will be moved laterally as the blades are moved longitudinally relative to the side plates.
